FIRE EXTINGUISHER

Filed Aug. 27, 1930

UNITED STATES PATENT OFFICE

1,926,762

FIRE EXTINGUISHER

Henry Archibald Ceaton, London, England, assignor of one-half to John Waugh Munro, Knowle, Warwickshire, England

Application August 27, 1930, Serial No. 478,230,
and in Great Britain August 28, 1929

8 Claims. (Cl. 169—2)

This invention relates to fire extinguishers of the kind employing a chemical agent or fluid contained in a receptacle of frangible material such as glass. The chief object of the present invention is to provide an improved fire extinguisher of the above kind that is particularly applicable for use in conjunction with prime movers either stationary or carried on road, rail or other vehicles.

According to the invention the receptacle containing the chemical fire extinguishing agent or fluid is completely mounted in a supporting unit comprising a bracket member or holder adapted to be secured to any convenient support, for example to a stationary part within the engine compartment of a vehicle, means operable from a distance being provided whereby in the event of fire, the receptacle can be broken to release the chemical agent or fluid. The said bracket member preferably carries the receptacle in a readily removable manner so that the latter may be used, when required, as a portable fire extinguisher and the construction of the bracket member may be of an adjustable nature, such as of two or more part form, so that the location of the receptacle relatively to the engine of the vehicle for example may be altered to suit varying conditions which obtain with different types of such vehicles with the object of releasing the liquid in as close proximity to the seat of the fire as possible.

In order that the said invention may be clearly understood and readily carried into effect the same will now be described more fully with reference to the accompanying drawing in which:—

Figure 1 is a front view of a preferred form of the bracket member, receptacle, and means for breaking the receptacle to release the contents thereof.

Figure 2 is a side elevation of Figure 1, and Figure 3 illustrates a detail to be described.

The supporting unit or bracket member comprises an elongated support A adjustably secured to which is a casing B for the receptacle C. The support A is in the form of an open ended trough having apertured wing plates a at one end whereby the support can be secured to the dashboard within the bonnet of a motor-car and apertures a² through one of which a bolt D passes which secures a casing carrier E to the support. The carrier is secured to the casing at its upper ends and is shaped at its lower end so as to fit the support A and so that it may be secured to the support in the position illustrated in Figures 1 and 2 or at right angles thereto. The apertures a²

permit adjustment of the carrier and casing longitudinally of the support. The receptacle C and the casing B are in the form of cylinders and the latter comprises a receptacle holder b and a closure b¹ therefor, the closure being hinged to the holder at b² on a horizontal axis and provided with a fastener b³. Secured by adhesive or otherwise within the holder are two semi-circular and fairly thick strips F of resilient material, preferably rubber of the kind known by the registered trade mark "Sorbo", and within the closure two corresponding strips F¹ are secured so that when the receptacle C is placed in the holder and the closure is fastened in position the strips F, F¹, will be compressed and will firmly grasp the receptacle. Opening the closure will release the receptacle so that it can be used as a portable fire extinguisher. Located within the casing and around the middle of the receptacle is a band H of piano wire bent inwardly into projections h. The wire is threaded at one end which is secured by nuts h¹ to the carrier E. The other end of the wire is attached by a connection j to one end of a wire J forming part of a Bowden wire device (the word "Bowden" being a registered trade mark) the outer jacket J¹ of which is attached to the carrier E by a connection j¹. The other end of the wire J is connected to a pedal lever or other suitable device (not shown) whereby it may be operated so that the piano wire is contracted about the receptacle which is broken or crushed by the projections h thereby releasing the fire extinguishing agent or fluid which flows through an aperture K in the lower part of the holder and from the ends thereof. Any of the fire extinguishing agent or fluid falling into the support A escapes through the perforations a². If desired the arrangement may be such that all the fluid falls into the support A which may have numerous perforations therein.

In a modified form of the invention illustrated in Figure 3 the manually operated means comprise an arm mounted on a pivot R¹ carried by the support A. The connection j is secured to the rear end of the arm and when the latter is operated its front end enters through the aperture K in the holder b and breaks the receptacle. The pivot R¹ is mounted in apertures R² in the sides of the support A, the apertures corresponding to the perforations a² so as to permit adjustment of the arm R in accordance with the position of the holder with respect to the support. The connection j¹ can be secured adjacent to any one of the perforations a².

What I claim and desire to secure by Letters Patent of the United States is:—

1. A fire extinguisher comprising a glass receptacle containing a fire extinguishing liquid, a cylindrical metal casing in which the receptacle is firmly held, said casing being made in two semi-cylindrical parts hinged together and having in its lower portion at least one opening direct to the atmosphere, fastening means normally holding the said parts together, a carrier secured to and supporting the casing, a bracket adapted to be attached to any suitable part of a motor vehicle and to which the carrier is adjustably secured, and means for breaking the receptacle operable from a distance.

2. A fire extinguisher comprising a glass receptacle containing a fire extinguishing liquid, a cylindrical metal casing in which the receptacle is firmly held, said casing being made in two semi-cylindrical parts hinged together and having at least one opening direct to the atmosphere, fastening means normally holding the said parts together which means can readily be disengaged so that said parts can be separated to permit removal of the receptacle for portable use, a carrier secured to and supporting the casing, an elongated trough shaped bracket located beneath the casing so that liquid escaping from the casing falls into the bracket to which the carrier can be secured at various points along the length of the bracket, said bracket having openings for the escape of the liquid and being adapted to be attached to any suitable part of a motor vehicle, and means for breaking the receptacle operable from a distance.

3. A fire extinguisher comprising a glass receptacle containing a fire extinguishing liquid, a cylindrical metal casing in which the receptacle is firmly held, said casing being made in two semi-cylindrical parts hinged together, and having at least one opening to the atmosphere, semi-cylindrical pieces of soft rubber secured to each semi-cylindrical portion of the casing and arranged to clamp the receptacle firmly when the two parts of the casing are closed, fastening means normally holding the said parts together, a carrier secured to and supporting the casing, a bracket adapted to be attached to any suitable part of a motor vehicle and to which the carrier is adjustably secured, said bracket being located beneath the casing so that liquid escaping from the casing falls into the bracket and said bracket having apertures for the escape of liquid and means for breaking the receptacle operable from a distance.

4. A fire extinguisher comprising a glass receptacle containing a fire extinguishing liquid, a metal casing in which the receptacle is firmly held, said casing having in its lower portion at least one opening direct to the atmosphere, a carrier secured to and supporting the casing, a bracket adapted to be attached to any suitable part of a motor vehicle and to which the carrier is adjustably secured, a flexible band surrounding the receptacle and having one end fixed, and means operable from a distance and secured to the other end of the band and adapted to contract the band for breaking the receptacle.

5. A fire extinguisher as in claim 4, wherein

the band is a ring of piano wire having inwardly projecting portions for engaging and breaking the receptacle when the band is contracted.

6. A fire extinguisher comprising a glass receptacle containing a fire extinguishing liquid, a cylindrical metal casing made in two semi-cylindrical parts hinged together, and having at least one opening direct to the atmosphere at its underside, semi-cylindrical pieces of soft rubber secured to each semi-cylindrical part of said casing and arranged to clamp the receptacle firmly when the two parts of the casing are closed, fastening means normally holding said parts together which means can readily be disengaged so that said parts can be separated to permit removal of the receptacle for portable use, a carrier secured to and supporting the casing, an elongated trough shaped bracket located beneath the casing so that liquid escaping from the casing falls into the bracket to which the carrier can be secured at various points along the length of the bracket, said bracket having openings for the escape of the liquid and being adapted to be attached to any suitable part of a motor vehicle, a flexible band within the casing and surrounding the receptacle and having one end fixed, and means operable from a distance and secured to the other end of the band and adapted to contract the band for breaking the receptacle.

7. A fire extinguisher comprising a glass receptacle containing a fire extinguishing liquid, a cylindrical metal casing made in two semi-cylindrical parts hinged together and having an opening direct to the atmosphere in its underside, semi-cylindrical pieces of soft rubber secured to each semi-cylindrical portion of said casing and arranged to clamp the receptacle firmly when the two parts of the casing are closed, fastening means normally holding said parts together, a carrier secured to and supporting the casing, an elongated trough shaped bracket to which the carrier can be secured at various points along the length of the bracket, said bracket having openings through which the liquid can pass and being adapted to be attached to any suitable part of a motor vehicle, a lever pivoted to said bracket and having one end adjacent to said opening and engaged to enter therein in fracturing relationship with said receptacle, and means operable from a distance and connected to said lever whereby the lever can be operated to move the end referred to through the aperture to break the receptacle.

8. A fire extinguisher comprising a glass receptacle containing a fire extinguishing liquid, a metal casing in which the receptacle is firmly held, said casing having at least one opening direct to the atmosphere, a carrier secured to and supporting the casing, a bracket adapted to be attached to any suitable part of a motor vehicle and to which the carrier is adjustably secured, a lever pivotally mounted on said bracket having an end adjacent to said opening and arranged to have said end enter into said opening in fracturing relation with said receptacle, and means for operating the lever from a distance to cause said end to enter the casing to break the receptacle.

HENRY ARCHIBALD CEATON.
